UNITED STATES PATENT OFFICE

LOUIS MARX, OF NEW YORK, N. Y., ASSIGNOR TO CHARLES J. CORRELL AND FREEMAN F. GOSDEN, BOTH OF CHICAGO, ILLINOIS

DESIGN FOR A VEHICLE TOY

Application filed March 31, 1930. Serial No. 35,075. Term of patent 3½ years.

To all whom it may concern:

Be it known that I, LOUIS MARX, a citizen of the United States, residing in the city, county, and State of New York, have invented a new, original, and ornamental Design for a Vehicle Toy, of which the following is a specification, reference being had to the accompanying drawing, forming a part thereof, wherein the figure is a perspective view of a vehicle toy, showing my new design.

Both sides of the body of the vehicle toy are the same, except that on one side of the body there is an entrance opening, while the corresponding part of the other side is provided with a simulated door.

I claim:

The ornamental design for a vehicle toy, substantially as shown and described.

LOUIS MARX.
